UNITED STATES PATENT OFFICE

2,501,972

DEPOSITOR AND APPLICATOR

Leon S. Seidler, Chicago, Ill.

Application July 31, 1946, Serial No. 687,278

3 Claims. (Cl. 128—263)

1

This invention relates to vaginal depositors and applicators and more particularly to one which may be extruded from its container and everted by a single operation after internal positioning.

The principal object of this invention is to provide an improved tampon or core which can be spread open and unfolded by a single manual operation.

The object of my invention is to provide a ready means of self-application and is a further improvement over the tampon covered by my pending application Serial No. 612,592, now Patent No. 2,430,250, in that the operation may be performed by one hand manipulation and the core is transversely folded to produce new and novel results.

In accordance with my invention there is produced a useful and practical device. It will remain sterile throughout the entire cycle of positioning, extrusion and eversion. It is easy to manufacture and low in cost. The extruded and everted core more readily conforms to the shape of the receiving cavity for more complete application. Its longitudinal and transverse folds provide an improved receptacle for medication prior to application. It is a complete device not requiring the use of additional instrumentalities.

Further objects of the invention will hereinafter appear from the following description of the preferred embodiment illustrative of the invention and shown in the accompanying drawing in which

Fig. 1 is a side view of the assembled device before operation.

Fig. 2 is a side view of the device after operation.

Fig. 3 is a front view of Fig. 2.

Fig. 4 is an end view of the ejector tube.

Fig. 5 is a side view of the tampon showing the transverse fold and attached draw string.

This internal depositing and applicating device consists of a U-shaped tampon with one end of a draw string attached to one of the open ends of the U, while the free end of the draw string is removably attached to the more remote end of the container tube. An ejector tube or other plunger is used to extrude the tampon from its container. One or both ends of the U-shaped tampon may be so anchored.

Referring to the drawings, the device therein shown comprises an internal depositing and applicating tampon 1, fashioned of absorbent material and transversely folded approximately in half at location 2. The tampon 1 is provided with a draw string 3, attached to outside sur-

face 18 at point 4 and with a depending end 5 knotted adjacent to its end at 19. The point 4 is adjacent to the crown 6 of the tampon 1. The free end of the tampon is indicated at 7. The complete fold at 2, provides a base part 8. The container tube 9 has an extrusion end 10 which is provided with an anchor slot 12. The ejector tube 13 is provided with an ejector end 14, a manipulation end 15, and a longitudinal indentation 16 extending between end 14 and end 15 resulting in a groove 17. A knot 19 separates cord 3 from its depending end 5.

In assembling the device, tampon 1 is folded at 2 forming a base part 8. Crown 6 is brought adjacent to end 1. Draw string 3 is brought contiguous to surface 18. This assembly is compressed and inserted into container tube 9 by passing base part 8 through extrusion end 10. Cord 3 is positioned between surface 18 and inside wall of container tube. The knot 19 is engaged with anchor slot 12 allowing depending end 5 to fall outside of the container tube 9. The ejector end 14 of ejector tube 13 is inserted into the anchor end 11 of container tube 9 until it touches the base part of the tampon. The lower portion of the draw string 3 lies within groove 17 of ejector tube 13 or between the walls of both tubes if no groove is provided. The provision of a groove allows free action of the draw string and also provides for greater bearing surface on ejector end 14.

In operating the device, pressure is applied to the manipulating end 15 of the ejector tube 13. The ejector end 14 of ejector tube 13 forces tampon out of extrusion end 10 of container tube 9. The tampon base 8 moves freely but draw string 3 extends only slightly as it is anchored on its lower end to container tube 9 as a result of knot 19 being engaged with anchor slot 12. The free end 7 of tampon 1 extrudes without interference. The crown end 6 being restrained by anchored draw string 3 is everted as shown. By disengaging knot 19 from slot 12 by means of depending end 5, both tubes may readily be removed.

It is apparent that the details of the device described may be varied without departing from the nature or principle of my invention and it is my intention not to limit the invention to the particular details set forth but to describe one method of obtaining the desired end so that said end, being once realized, may be accomplished by changes in the construction and arrangements of the several parts, provided that such changes fall within the scope of the appended claims.

Having described the preferred embodiment illustrative of my invention, I claim:

1. A depositor and applicator comprising a flexible transversely folded expellable tampon having a base part, a free end, an anchored crown and a depending anchor string and cylindrical concentric inner ejector and outer container tubes therefor, the lower end of said container tube being provided with an anchor slot, said tampon being entirely inserted into said container tube through its upper end with the base of said tampon within the tube, the upper end of said string being permanently attached adjacent to the end of said crown and depending from the outside surface of said crown, the lower end of said string being fastened to said anchor slot, the length of said string from said crown to said slot being substantially the same as the length of said container tube, the length of said ejector tube being shorter than the length of said container tube after full insertion of said ejector tube.

2. A depositor and applicator comprising a flexible transversely folded core having a base part, a free end, an anchored crown and an anchor string attached to said crown, and a cylindrical tube container for said core, said base part being inside of said tube and said crown and said free end being contiguous to the upper end of said tube, said crown being tied to the lower end of said tube by said draw string, said tube

containing a shorter concentric inner ejector tube.

3. In an internal depositing and applicating device of the kind described, an expellable expanding core, and concentric cylindrical shorter inner ejector and longer outer container tubes therefor, said core comprising longitudinally an anchored crown, a free end, and a base part, said core being compressed transversely into a substantially cylindrical shape, and enclosed in upper end of said container tube with said base part within said tube, said crown being provided with an anchor string permanently fastened on one end to its outside surface, the lower end of said container tube being provided with an anchor slot, the other end of said anchor string being connected to said anchor slot.
